SUCTION CLEANER

Dale C. Gerber, North Canton, Ohio, assignor to
 The Hoover Company, North Canton, Ohio, a
 corporation of Ohio

Application October 23, 1946, Serial No. 705,174

17 Claims. (Cl. 183—58)

1

This invention relates to suction cleaners and more particularly to a novel filter-shaking device incorporating means for informing the user when it is being properly operated.

Prior filter-shaking devices make use of comparatively strong springs for snapping the filter to taut condition in order to dislodge dirt accumulated thereon. Such strong springs are deemed essential for the effective operation of certain shaker designs. However, they have the disadvantage of requiring considerable operating force on the part of the user. Since the filter is not exposed to view, the user is unable to tell when the spring has been stressed sufficiently to provide an adequate shaker operating force with the result that the filter may not be cleaned to any appreciable extent even though the shaker has been operated several times.

It is therefore an object of the present invention to provide a novel suction cleaner which overcomes defects in prior constructions. More specifically, it is an object of this invention to provide a cleaner having a new and improved filter-shaking mechanism. A further object is the provision of a filter shaker incorporating means for informing the user when it is being operated properly and improperly. Still another object is the provision of a filter-shaking mechanism having associated therewith a signal device. Another object is to provide a shaker which automatically advises the user that it has been so operated as to restore the efficiency of the filter.

Still further objects are to provide a novel combination filter shaker and signal device which is very simple in construction, low in cost and highly effective for its intended purposes.

These and other objects will become apparent upon reading the following specification and claims and the accompanying drawings showing a preferred embodiment.

Figure 1 is a side elevational view of a tank type suction cleaner illustrating a preferred embodiment of my invention.

Figure 2 is a sectional view of a part of the shaker mechanism and associated signal taken along the line 2—2 on Figure 1.

Figure 3 is an isometric view of a modified form of signal device which emits an audible signal after a pre-determined number of effective shaker operations.

Referring now to Figure 1, it will be seen that my invention has been incorporated in a tank type cleaner having an outer casing 10, the opposite ends of which are closed by means of end caps 11 and 12 respectively. These are provided

2

with adapters 13 and 14 provided with air inlet and air outlet passages, respectively, and each of which is adapted to receive the usual cleaning tool attachments. Cap member 11 is releasably held in place by toggle clamp 15 while cap 12 may be semi-permanently secured to the casing by screws or other equivalent means.

The casing is mounted upon runners 16 to facilitate movement of the cleaner about the room or space being cleaned. Secured to the top of the casing is a carrying handle 17 and an operating control switch 18.

Suitably mounted interiorly of the casing and toward one end thereof is a conventional type of motor-driven suction fan unit 19 having an axially disposed inlet port 20 and radially disposed discharge ports 21. A screened grill 22 may be mounted over the air inlet port to prevent foreign objects from entering the fan chamber.

A filter bag 23 of suitable air pervious material occupies a major portion of the casing and has an open end secured to the casing interiorly of end cap 11. A spider, not shown, is enclosed within the inner interior end of the bag and has its central portion secured to the inner end of a supporting bracket arm 24. This arm is L-shaped and, as shown, has its longer leg 25 slidably mounted along the lower interior side of casing 10. An operating handle 26 is attached to the outer end of arm 24 and is movable along a slot, not shown, in the lower side of the casing.

Secured to the opposite side of bracket 24 and extending along the lower interior side of the casing opposite arm 25 is a filter driver spring guide rod 27. Intermediate the ends of this rod is a bracket 28 which serves to guide the rod and also as an abutment for the filter drive spring 29. It will thus be apparent that the relatively strong filter drive spring 29 functions normally to maintain filter bag 23 under very considerable tension thereby permitting the bag to function at maximum efficiency.

Incorporated with the bag shaker mechanism is my novel signal device. This comprises a mass of metal 30 which is freely slidable on the outer end of guide rod 27. A relatively light compression spring 31 is interposed between bracket 28 and metal mass 30 and normally maintains the latter against the adjustable lock nuts 32. As will be readily understood, nuts 32 permit adjustment of the stress on spring 31 which governs the operation of the signal device.

Mounted upon the interior side of the casing opposite bracket 28 is a gong 33. The position of the gong may also be made adjustable if so

desired. A resiliently mounted clapper 34 extends laterally from metal mass 30, and is so disposed relative to the gong that it will strike the same only when the inertia imparted to metal mass 30 by filter drive spring 29 is great enough to overcome spring 31 and permit the clapper to strike the gong.

Referring now to the modification of my invention illustrated in Figure 3, it will be observed that substantially the only change involves a modified signal device located at the outer end of the filter spring guide rod. Primed numerals are employed to designate elements having their counterpart in the preferred form.

The alternative signal device is mounted upon a base plate 35 which may be curved to fit against the inner side of the cleaner casing at a point beneath the outer end of the filter guide rod 27'. This guide rod is slidably supported by an upturned support 28' which is adapted to form one of the abutments for the filter drive spring 29'. If desired, a resilient buffer cushion 36 may be interposed between the end of the drive spring and support 28'.

A metallic mass 30' is slidably mounted on the outer end of rod 27' and is normally held against lock nuts 32' by a light tension spring 31'. Pivotally supported on mass 30' is a pawl 37 which cannot rotate counterclockwise beyond the position shown in Figure 3. However, it may rotate as much as 90° clockwise against the action of a light spring 39. Rotatably mounted in the path of travel of the pawl is a star wheel 40 which is designed to rotate counterclockwise as viewed in Figure 3. This wheel may be called a metering or tallying device since it functions to count the number of proper shaker strokes and to operate the signal after a pre-determined number of such strokes have been completed. A leaf spring 41 is mounted on base plate 35 and extends into engagement with the teeth of the star wheel for the purpose of permitting the same to rotate one tooth at a time but operative to prevent clockwise rotation as will be obvious from the drawing. One only of the segments of the star wheel is provided with a downturned flange 42. Pivotally supported to one side of the star wheel is a bell crank 43 having a short arm 44 extending into the path of flange 42. Its opposite end 45 carries a bell clapper 46 normally held near gong 33' by a tension spring 47.

My invention operates as follows: Referring first to the preferred embodiment shown in Figures 1 and 2, it will be understood that when the operator desires to restore the operating efficiency of the filter by removing dirt accumulated on the inner walls thereof, it is merely necessary to up-end the cleaner or to turn it on its side so that the filter operating handle 26 is conveniently accessible. This handle is then moved longitudinally of the casing with the result that the filter bag is collapsed and driving spring 29 is compressed to a high degree. Upon release of the operating handle, the drive spring will expand rapidly carrying the filter supporting bracket 24 toward the motor fan unit and snapping the filter bag to a taut condition with a vigorous action. If the operator has compressed the driving spring to such an extent that it has adequate stored energy to snap the filter properly, then sufficient inertia will be imparted to the slideable mass 30 to compress the relatively light spring 31 and permit the clapper to sound gong 33. Immediately following a single sounding of the gong, mass 30 and clapper 34 will be returned

by spring 31 to a position against lock nut 32. It will be apparent that if the filter drive spring 29 has not been sufficiently compressed by the operator, mass 30 either will not slide forwardly on the guide rod or will not move far enough to sound the gong. Thus, even though the operator cannot see the filter, he is advised immediately as to whether or not the shaker mechanism has been so operated as to shake the same properly. If the gong does sound, he is assured that the cleaning efficiency of the filter has been restored.

The operation of the modified construction is similar to that described above for the preferred embodiment except that a pre-determined number of proper shaker operations is required to actuate the signal device. This is accomplished as follows: The shaker handle is operated as described above with the result that upon each release thereof metallic mass 30' will move forwardly along guide rod 27' and pawl 37 will rotate star wheel 40 through one increment. After a single operation, the metallic mass is returned by tension spring 31' to its position against adjustable stop 32' on the end of the drive rod. Spring 39 on pawl 37 permits the latter to override the adjacent tooth of the star wheel so that it will be in position to again rotate the wheel upon the next operation of the shaker mechanism. The star wheel is prevented from rotating clockwise during this operation by reason of the locking action of leaf spring 41. If the operator fails upon any operation of the shaker to compress the driving spring adequately, mass 30' will not move forward along rod 27' and consequently pawl 37 will not rotate the star wheel. However, after a plurality of proper operations of the shaker, depending upon the number of teeth on the star wheel, the latter will have been rotated sufficiently to permit flange 42 of the wheel to operate bell crank 43 and clapper 46 to sound gong 33'.

While each of the above described modifications and others which fall within the scope of this invention may be operated to shake the filter either during operation of the cleaner and without removing the end cap 11, yet the arrangement has particular utility as an aid in thoroughly cleaning the filter during dirt emptying operations. To accomplish this it is merely necessary to remove end cap 11 by releasing clamp 15 and to up-end the cleaner so that its exposed end rests upon a sheet of paper or a dirt-receiving receptacle. It will then be understood that the accumulated dirt as well as that adhering to the side walls of the filter can be removed very simply without removing the filter from the cleaner and while the latter is held by its own weight in airtight relation to the dirt-receiving surface. After the signal device has advised the operator that the shaker mechanism has been properly operated, the cleaner is returned to rest upon its runners and the end cap is replaced so that the cleaner may be returned to normal operation.

While I have shown and described but two embodiments of my invention, it is to be understood that these are to be taken as illustrative only and not in a limiting sense. I do not wish to be limited to the specific constructions shown and described but to include all equivalent variations thereof except as limited by the scope of the claims.

Having thus described my invention what I claim is:

1. Shaker mechanism for a suction cleaner filter comprising movable supporting means for a filter bag, spring means biasing said support to

a normal position in which a wall of a filter is maintained taut, manually operable means for moving said supporting means so as to remove the tension on said filter wall and to increase the tension on said spring means, signal means, and means interconnecting said shaker mechanism and said signal means operable to actuate said signal from energy provided by said spring means when returning said filter wall to a taut condition after operation of said manually operable means.

2. A filter shaker mechanism as defined in claim 1 characterized in that said interconnecting means and said signal means includes means for actuating said signal after a plurality of separate operations of said shaker mechanism.

3. The combination with a suction cleaner comprising a casing having an air inlet and an air outlet, a filter supported in said casing between said inlet and said outlet, shaker mechanism connected to said filter for dislodging dirt therefrom, said mechanism including spring means normally operative to tension the walls of said filter, manually operable means for collapsing said filter in opposition to said spring means so that upon release of said manual means said spring means snaps the walls of said filter taut abruptly to dislodge dirt, of signal means associated with said shaker mechanism for apprising the operator whether said shaker mechanism is being operated in a manner to shake said filter effectively, said signal means being normally inactive, means for momentarily activating said signal means including means operatively connected with said shaker mechanism and operable upon a predetermined movement of the same to shake said filter to activate said signal means.

4. The combination defined in claim 3 wherein said signal means includes a gong, and wherein said means for activating said gong includes a striker for sounding said gong.

5. The combination defined in claim 3 wherein said means for activating said signal means comprises a weight movably supported upon a movable portion of said shaker mechanism, light spring means for holding said weight against an abutment on said shaker mechanism so long as said shaker mechanism is stationary or is being moved in opposition to said spring means acting on said filter but permitting said weight to move relative to said shaker mechanism to activate said signal means when the movement of the shaker mechanism is abruptly stopped by the tensioning of said filter walls.

6. The combination of a filter shaking mechanism and a signal means therefor operable to activate said signal when said shaker is being operated to shake a filter effectively comprising, a filter, stationary means for supporting one part of said filter, movable supporting means connected to another portion of said filter including a stiff shaker spring normally holding the walls of the filter taut, manual means for moving said movable supporting means in opposition to said shaker spring to relax the tension on said filter whereby said spring snaps said walls taut abruptly when said manual means is released, signal means, and means positioned in the path of said movable filter support when the same is operated to shake said filter and operable by the movement of said movable support to activate said signal means.

7. The combination with a filter bag and a shaker mechanism therefor of the type in which the filter is collapsed in opposition to a spring and suddenly released for abrupt tensioning by

said spring to dislodge adhering dirt, of a signal device arranged to be activated in response to the collapsing of said filter to a predetermined extent, said signal device comprising audible

5 signal emitting means, means for energizing said signal emitting means including means located in the path of movement of said shaker mechanism and actuatable upon a predetermined movement thereof in collapsing said filter to energize said signal emitting means momentarily as said filter is tensioned.

8. The combination defined in claim 6 wherein said signal device includes a tallying mechanism located between said shaker mechanism and said audible signal emitting means, the arrangement of said shaker and tallying mechanisms being such that the movement of said shaker mechanism in shaking said filter advances said tallying mechanism through one increment each time said shaker is manually operated, means for holding said tallying mechanism against retrograde movement, and means actuated by said tallying mechanism after the same has been advanced a predetermined number of increments for energizing said signal emitting means whereby the operator is advised that said shaker mechanism has been operated in a satisfactory manner to shake said filter.

9. The combination with a filter for a suction cleaner and a shaker mechanism therefor of the type which alternately collapses and tensions a wall of the filter abruptly to dislodge adhering dirt, of a tallying device, a mass movable upon actuation of said shaker to advance said tallying device one increment for each operation of said shaker, a signal device, and means responsive to the advancement of said tallying device through a predetermined number of increments to actuate said signal device.

10. In a suction cleaner, a filter therefor, a shaking mechanism for said filter of the type having a spring for tensioning said filter walls abruptly when said spring is compressed and then released, a signal device operative to give a signal when said spring is compressed sufficiently to tension said filter abruptly and with a predetermined force comprising signal means, means for activating said signal means including means located in the path of said shaking mechanism so as to be moved thereby to activate said signal when said spring has been compressed to a predetermined extent.

11. In a suction cleaner, a casing having an opening, a filter bag within said casing having an opening in communication with said casing 55 opening, supporting means attached to said filter at a point opposite the opening therein, means normally operative to maintain side walls of said bag taut and movable to a position in which said walls are loose and at least partially collapsed, means for restoring said walls from a partially collapsed to a taut condition abruptly and with a snapping action to dislodge dirt adhering thereto, signal means, means for activating said signal means, said activating means including means located in the path of movement of said means for maintaining the walls of said bag taut and movable thereby to actuate said signal activating means if said bag has been collapsed to a predetermined extent.

12. In a suction cleaner, a filter means, shaker mechanism therefor of the type which is manually depressed to collapse the filter means in opposition to a spring and is then released permitting the spring to snap the walls of the filter

taut abruptly to dislodge dirt, normally inactive signal means associated with said filter means and shaker mechanism adapted to be activated momentarily when said shaker is manually depressed to the extent required to shake said filter effectively, said signal means including means movable with said shaker as the same is manually depressed in opposition to said spring and which is movable to a limited extent independently of said shaker by inertia action as the return movement of said shaker is arrested abruptly by the tensioning of said filter walls, and means actuated by the independent movement of said last mentioned means to a predetermined extent for momentarily activating said signal means whereby the operator is apprised as to whether said shaker mechanism is operating properly.

13. A suction cleaner as defined in claim 12 wherein said signal activating means includes a tally device adapted to be advanced one increment by said activating means for each complete operating cycle of said shaker, and means operated by said tallying device after the same has been advanced a predetermined number of increments for activating said signal means.

14. Shaker mechanism for a suction cleaner filter comprising movably mounted means for supporting one end of a filter bag, spring means normally biasing said filter supporting means in a direction to maintain walls of a filter taut, manually operable means to move said filter support against the action of said biasing means to collapse the walls of a filter supported thereby whereby said spring means tensions said filter abruptly to dislodge dirt therefrom when said manually operable means is released, audible signal emitting means, striker means for said signal means, and actuating means operatively connected with said shaker mechanism for moving said striker means against said signal means upon a predetermined movement of said shaker mechanism to shake said filter.

15. A filter shaker mechanism as defined in claim 14 characterized in that said interconnecting means includes inertia responsive means operable to actuate said signal means provided said filter supporting means is moved to a predeter-

mined extent before being released for return to a taut filter supporting position by said biasing means.

16. A filter shaker mechanism as defined in claim 14 characterized in that said interconnecting means includes a member movable with respect to said manually operable means and actuatable by energy supplied by said biasing means to sound said audible signal means provided said shaker mechanism has been operated to a predetermined extent to shake a filter and dislodge dirt therefrom.

17. In combination, a suction cleaner of the tank type comprising an elongated housing, a motor fan unit in one portion thereof and a collapsible filter bag mounted in another portion thereof, means operable to shake said filter to dislodge adhering dirt and to maintain the walls thereof normally under tension, said means including a member extending longitudinally of said housing with a portion opposite said motor fan unit and a portion opposite said filter, an operating handle attached thereto and extending to a point exteriorly of said casing, signal means, and inertia responsive means operable to actuate said signal means when said shaker has been collapsed to a predetermined extent whereby the operator is advised that the filter has been effectively actuated.
